[57] **ABSTRACT**

An extractor which has a clamp head operating on a universally jointed handle enables the operator to engage and easily remove the spring steel lock retaining clip that holds locks onto car doors or like sheet metal areas.

ATTORNEYS

1
EXTRACTOR FOR LOCK RETAINER CLIPS

This invention pertains to a tool used in locksmithing and more particularly pertains to a device for extracting the retaining clip that holds locks to sheet metal closures such as automotive doors and trunks.

BACKGROUND OF THE INVENTION

The lock commonly found on the doors and trunks of automobiles, trucks, and other similar equipment is generally of the cylindrical type. The lock is installed by cutting a hole in the sheet metal of the area where it is to be implaced, pushing the tumbler portion of the lock through the opening and then holding the tumbler in place with a retaining clip. The outer portion of the lock lies in a washer type arrangement which gives a smooth appearance to the outside portion of the lock and in addition gives no gripping points for removing the lock. The tumbler portion of the lock is usually provided with two slots or knurls or similar means disposed on opposite sides of the tumbler. A U-shaped steel spring clip is designed to slide into the grooves, or under the knurls, and by a wedging action against the interior face of the sheet metal maintain the lock securely in the door.

The automotive door or trunk lid is usually constructed of two sheets of metal, one forming the outer part of the door and the other the inner part. The outer one is sculptured to whatever design is desired by the manufacturer and the inner one is formed to give thickness to the door so as to provide a boxlike structure. Access to the inside of this door structure is provided by a number of entry ports or holes in the inner formed sheet metal part of the door metal. In order to service the equipment found in the door, such as lock mechanisms, door-operating mechanisms and window mechanisms, it is necessary to operate through these entry ports and around the other parts found in the door.

The lock-retaining clip is, in theory, fairly easy to remove. It is only necessary to grasp an upright lip provided on the rear of the clip and pull upward and outward. Unfortunately the clip is located on the interior side of the outer metal sheet and is usually inaccessible to a human hand holding a pliers. Various means have to be used in an attempt to remove the clip. These methods include attempts to pry the clip off with screwdriver, pry bar, or whatever tool can fit into the opening and still permit digital manipulation. These bouts of man and inanimate object often result in an expenditure of time on removing and inserting the clip which is out of all proportion to the actual work which has to be performed on the lock itself. In addition there is often a loss of skin and blood by the workman in trying to manipulate these clips.

Therefore it is an object of this invention to provide an extractor which can easily be positioned at the clip.

It is a further object of this invention to provide a extractor which positively engages the clip.

It is another object of this invention to provide an extractor which is substantially manipulated from outside the confines of the door.

Yet another object of this invention is to provide an extractor which can be used for reinserting the clip in its proper position.

Other objects of this invention will become apparent in the following description.

SUMMARY OF THE INVENTION

This invention contemplates a tool useful for extracting lock retaining clips, which clips are designed to hold and mount locks on sheet metal structures or the like. The extractor has a screw member which is operably mounted in a clamp head and cooperates with the head to provide the clamping action. A handle is connected to the screw member by means of a universal joint thereby permitting the operation of said screw member by the handle regardless of their relative position.

2

BRIEF DESCRIPTION OF DRAWING

FIG. 1 is a full perspective top view of the device showing the slide sleeve in the closed position and a clip shown in shadow.

FIG. 2 is a rear perspective view showing the slide sleeve drawn back and an alternate embodiment of the handle.

FIG. 3 is a detail of top view of the device.

DESCRIPTION OF AN EMBODIMENT

Now having generally described the extractor of this invention, reference is made to the drawings to describe a specific embodiment of the invention.

Referring now to the drawing, FIG. 1 shows an extractor 10 which has a clamp head 11. The clamp head is shown gripping a spring lock retaining clip 12. The clamp head is a frame having two stationary vertically disposed uprights 13 and 14 which define a U-shaped guide way 15. The facing walls 16 and 17 of the uprights 13 and 14 are at least one-eighth of an inch in height as measured from the closed portion 18 of said U-shaped guide way 15. It is not necessary that the uprights be stationary. In another embodiment (not illustrated), at least one of the uprights can be movable and apply the gripping pressure. The guide way need only be as deep as necessary to receive a portion of the lip 112 of the clip 12, but preferably grips substantially the entire lip 112 of the clip 12. Uprights 13 and 14 have beveled edges 20 and 21 which facilitates alignments of the lip 112 of the clip 12 in guide way 15. (FIGS. 1 and 3).

Referring now to FIG. 3, the clamping action is provided by a screw member 19 which is operably mounted in upright 14 of clamp head 11 and cooperates with wall 17 of upright 13 to engage the retainer clip when it is inserted in groove 15. The screw member 19 is positioned in upright 14 so that it will exert a strong force against the lip 112 of the clip 12. The screw member is positioned at least one-sixteenth of an inch below the open end of the guide way 15. The screw member 17 is so positioned that its contact point is centered on wall 17 of upright 13. The screw member 19 is operated by means of a handle 22 (FIGS. 1, 2 or 3). The handle is connected to the screw member 19 by a universal joint 23. The universal joint has a central rod member 24 with tongues 25 and 26 disposed on opposite ends of central rod member 24. The principal plane of tongues 25 and 26 are turned 90° to each other. The tongue 25 is inserted in slot 27 of screw member 19 and pivotally held there by pin 30. In like manner tongue 26 is inserted in slot 27 of handle 22 and pivotally held in place by pin 29. The universal joint 23 connecting the screw member 19 and the handle 22 permits operation of the screw member 19 by the handle 22 regardless of their relative positions. Any universal joint configuration which can transmit force parallel to the long axis of the joint, without deforming, is operable within the concept of this invention. Such universal joints are illustrated on pages 260-263 of *Engineer's Illustrated Thesaurus*, by H. Herkimer, Chemical Publishing Co., New York (1952), particularly preferred universal joints are the Boston Gear Works type joint, the ball and socket joint and the universal joint with gimbal ring. A flexible coupling can be used in place of the universal joint but this type of coupling is not preferred unless it can withstand the force lines transmitted parallel to the long axis of the joint when pulling or pushing force is exerted on the device in removing or inserting the retainer clip 12.

In the preferred embodiment of the invention a slide sleeve 31 is slidably mounted on handle 22 to selectively permit and restrict the free movement of the universal joint 23. In FIG. 1 the slide sleeve 31 is illustrated in closed position covering universal joint 23. In the closed position the slide sleeve 31 makes the entire device rigid and thereby facilitates the guidance of the clamp head through the internal mechanisms of an automotive door or trunk lid to the work site. In FIG. 2 the slide sleeve is shown in a retracted position exposing the universal joint 23 and allowing the handle 22 to operate the

screw member 19 regardless of their relative positions. A stop member 32 is mounted on the handle 22 to restrict the movement of the slide sleeve 31. The stop 32 can be integrally formed on the handle 22 by bending or pinching the metal as is known in the art or it can be a separate piece such as a rubber doughnut movably mounted on the handle 22. The stop 31 is positioned on the handle so as to allow the slide sleeve 31 to be retracted to a position which allows the free movement of the universal joint 23.

The handle 22 terminates in a leverage aid which can be a disc 33 in slot 34 illustrated in FIG. 1 or a bent handle 35 illustrated in FIG. 2. Any of the commonly used leverage aids such as knobs, knurling, hooks, rings, etc., can be used on the handle to improve the gripping and turning force of the device.

In operation, the lock clip is first exposed by removing the inner door panel or locating the lock if it is a trunk lid lock or similarly positioned lock. The slide sleeve 31 is then placed in the closed position resting against the back of clamp head 11. The clamp head 11 is rotated a few turns so that the screw member 19 is disengaged from contact with face 17 of upright 13. It is preferred that screw member 19 actually be behind the face 16 of upright 14. The device 10 is then inserted through a hole in the door and positioned so that the lip 112 of the retainer clip 12 is in the guide way 15. The slide sleeve 31 is then retracted, exposing universal joint 23, and the handle 22 is manipulated from any convenient position, preferably outside the door frame, until the screw member 19 tightens against the lip 112 of clip 12 clamping the lip 112 of clip 12 securely against face 17 of upright 13. A pulling force is then exerted on the handle 22, which is conveniently outside the cramped space of the door frame, and the clip 12 readily removed. The lock is then removed from the outside of the door and serviced. When the lock is to be reinstalled it is positioned in the door and the clip 12 clamped into the clamp head 11 in the manner previously described. The slide sleeve 31 is placed in the closed position thereby providing a rigid tool. The clip 12 is then guided to its proper position and by the application of a pushing force on the handle 22 and the clip 12 reset in its proper position. The slide sleeve 31 is then retracted and the clamping pressure of screw member 19 released by manipulating the handle 22. The tool is removed and the finishing work, such as replacing door panels completed. By the use of the device the operation is completed rapidly without damage to either the clip, lock or workman.

Although the invention has been particularly disclosed for a

device with a screw clamp it is to be understood that the invention is applicable for other types of clamp heads operable through a universal joint. It is also obvious to one of ordinary skill in the art that the foregoing is presented by way of example only and the invention is not to be unduly restricted thereby, since modifications may be made in the tool without departing from the spirit of this invention.

I claim:

1. An extractor for lock retainer clips comprising a clamp head, a screw member operably mounted in said clamp head and operably cooperating with said clamp head, a handle, and a universal joint connecting said screw member and said handle so as to permit operation of said screw member by said handle regardless of their relative positions.
2. An extractor according to claim 1 wherein said clamp head is a frame having two stationary uprights substantially defining a U-shaped guide way, and said screw member is operably positioned in one of said uprights so as to cooperate with the other of said uprights to provide a clamping force.
3. An extractor according to claim 2 wherein the uprights are at least one-eighth of an inch high as measured from the closed portion of the U-shaped guide way.
4. An extractor according to claim 2 wherein a sleeve is slidably mounted on said handle and positioned to selectively expose or cover said universal joint.
5. An extractor according to claim 4 wherein a stop means is mounted on said handle to restrict the movement of said slide.
6. An extractor according to claim 5 wherein the uprights are at least one-eighth of an inch as measured from the closed portion of the U-shaped guide way.
7. An extractor according to claim 1 comprising a clamp head having vertically disposed facing walls defining a U-shaped guide way; a screw member operably disposed in an upright and passing through one of said walls and cooperatively engaging the other of said walls to provide a clamping action, said walls being at least one-eighth of an inch as measured from the closed portion of said U-shaped guide way; a handle; a universal joint connecting said screw member and said handle so as to permit operation of said screw member by said handle regardless of their relative positions; a sleeve slidably mounted on said handle and positioned to selectively permit and restrict the free movement of said universal joint and a stop means positioned on said handle so as to engage and limit the travel of said sleeve.
